(57) **CLAIM**

The ornamental design for a probe handle for thermometer, as shown and described.

DESCRIPTION

FIG. 1 is a front perspective view of a probe handle for thermometer with parts of a thermometer probe other than the probe handle shown in phantom;

FIG. 2 is a front elevational view thereof;

FIG. 3 is a rear elevational view thereof.

FIG. 4 is a left side elevational view thereof.

FIG. 5 is a right side elevational view thereof.

FIG. 6 is a top plan view thereof;

FIG. 7 is a bottom plan view thereof; and,

FIG. 8 is a rear perspective view of the probe handle in combination with the probe.

Portions of the views shown in phantom form no part of the design.
